METAL TUBE CONSTRUCTION

Clarence A. Horn, Roselle Park, N. J., assignor to
 Arcturus Development Company, Newark, N. J.,
 a corporation of Delaware

Application January 24, 1936, Serial No. 60,588

14 Claims. (Cl. 250—27.5)

This invention relates broadly to sealed metal tubes for electrical devices and appliances. More specifically, the invention pertains to sealed metal vacuum tubes employed in the radio art, and to an improved means for supporting the electrical elements and lead-in wires within the metal shell or container.

The use of metal tubes has become general in the radio field on the ground that the metal construction overcomes possible deficiencies in the glass type tubes. It is claimed, for example, that the metal tubes overcome considerable breakage both in use and in manufacture; permit more economical use of space because of the small size of the tube, and other advantages. There are inherent difficulties in metal tubes, however, such as the increased danger of short circuiting between the lead-in wires and the metal of the shell, and the increase of detrimental capacity effects arising from the close positioning of the lead-in and support wires of the tube to the shell.

It is an object of the present invention, therefore, to provide an improved construction in the seal between the lead-in wires and the metal container of a radio tube or the like.

Another object of the invention is to provide a type of seal for metal tubes which permits an important reduction in the length of the stem, and consequently in the length of the radio tube, thereby permitting the manufacture of tubes of small size.

Still another object of the invention is to provide a metal tube construction in which the entire electrode unit is assembled on a single insulating stem support such as glass.

An object also is to provide a seal for metal tubes which permits a considerable reduction of detrimental inductive and capacity effects between the various conductors mounted within the tube.

An additional object is the provision of an improved process for making a tube of the metal envelope or shell type wherein the stem is formed entirely of glass appropriately sealed to the base of the metal shell.

Further objects will become apparent on consideration of the following description of embodiments of the invention which may be preferred and of the process of manufacturing the same, as well as of the accompanying drawings, in which:

Fig. 1 is a view of the stem unit showing the exhaust tube, lead-in wires and supports in position;

Fig. 2 is a view partly in section showing the stem in position on the fixture used in the stem welding machine in connection with the modification of Fig. 7;

Fig. 3 is a plan view of the turret machine 5 employed in the welding operation, particularly in the stem welding operation;

Fig. 4 is an elevation partly in section of a rotatable head of the stem welding machine showing the stem associated with the ring or 10 hollow disc to which it is to be welded;

Fig. 5 is an elevation partly in section of a completed radio tube embodying my invention;

Fig. 6 is a view of a section of the base of a completed tube showing a modified combination 15 of stem and disc;

Fig. 7 shows a further modification of the stem-disc combination; and

Fig. 8 is still another modification of the disc and stem.

In accordance with my invention I utilize the form of stem unit as described in my co-pending application Serial No. 53,848, filed December 11, 1935, which is Patent 2,107,254 of February 1, 1938. As described in this co-pending application, the various lead-in wires are inserted in a short tubular stem having, preferably, one end flared and the other end welded in a stem-making machine to form a glass wall in which the various lead-in and support wires 30 are embedded. This sealing operation is facilitated, and in certain constructions made more secure and efficient, by placing a glass bead around each of the lead-in wires in the approximate plane of the weld so that the heat used in the manufacture of the stem causes both the stem end wall and the beads to flow together.

A stem made in accordance with the process of this co-pending application has ample area for the separation of the lead-in wires sufficient to 40 prevent undue inductive and capacity effects between them. Further, the construction permits formation of a stem of relatively short length so that short length tubes may be easily constructed with stems of this type, an example of 45 which is shown in Fig. 1, wherein the stem unit is designated by the numeral 10 and the parts include the stem 11 having a flared end 12 and a glass wall 13 in which are embedded the various lead-in wires 14, the support wires 15 and 50 the exhaust tube 16.

Generally speaking, the method of attaching a stem of this type to a metal shell, envelope or container such as indicated by the numeral 17 of Fig. 5, consists in interposing between the 55

open edge of the shell and the flared edge 12 of the stem a metal ring or disc 18, and by suitable heat welding operations sealing the disc to both stem and shell. The stem weld between the flare 12 of the stem 11 and the ring 18 is accomplished on a machine of the type basically similar to the well-known Charles Eisler type stem-making machine.

As shown in Fig. 3, the machine 20 includes the turret 21 rotatable on the base 9 in the direction of the arrow, as shown, and on which are mounted the independently rotatable heads 1, 2, 3, 4, 5, 6 and 7. These heads, in the circular motion of the turret 21, are subjected to gas flames of varying intensity, indicated by the numeral 140, there being in the first heat four jets in opposed groups 23 of two each, then in sequence ten jets in opposed groups 24 of five each, twelve jets in opposed groups 25 of six each, and six jets in opposed groups 26 of three each. These various jets are supplied from appropriate pipe connections, those on the turret coming from supply pipes rising through a central header connection and distributed through the various pipes 27. The number of jets is, of course, arbitrary and may be varied to suit conditions.

Power for driving the turret 21 of the stem welding machine is obtained from the electric motor 30 which is belted to a pulley wheel 31 mounted on the stub shaft 32 which in turn drives through the gears 33 and 34 to the main driven shaft 35 lying crosswise beneath the turret and base 9. The shaft 35 is provided with the worm gears 36 and 37. The worm 36 contacts with the worm wheel 37' mounted on a stub shaft 38 on which are also mounted the sprocket gear 39 and the rubber-faced wheel 40. The sprocket gear 39 meshes with the chain 41, which in turn meshes with sprockets 42, 43, 44 and 45 on vertical shafts 46 mounted at spaced intervals about the turret adjacent to the rotatable heads 2, 3, 4 and 5. Also mounted on these shafts are the rubber wheels 47, 48, 49 and 50 which are adapted to engage cooperating gears in the heads to bring about rotation thereof, as will hereinafter be more fully described.

The worm gear 37 on shaft 35 cooperatively engages a worm wheel 51 mounted on a vertical shaft and carrying an arm 52 provided with an upstanding pin 53 forming a member of a Geneva gear. The cooperating Geneva gear member 54 is of the usual construction including a disc with a plurality of radially projecting gear teeth 55 having outer concave curved edges 56 separated by radial recesses 57 in which the pin 53 is adapted to engage and cause a limited rotation of the Geneva gear 54 and the attached turret 21. As shown in this drawing, the shaft supporting the worm wheel 51 supports also the disc 58, the periphery of which has a curvature similar to that of the concave edges 56 of the gear teeth 55 of the Geneva gear 54 and is adapted to rotate with the disc edge and gear edge 56 in contact with each other except when the pin 53 is in engagement with the recesses 57 of the gear 54, at which time the gear teeth 55 have freedom of movement by reason of the formation of the disc 58 with a cut-away portion 59 adjacent the arm 52. During one complete rotation of the disc 58 and the associated pin 53 the gear 54 is rotated one-seventh of its circumference to bring about a similar movement of the turret 21 and thereby cause movement of the rotatable heads 1 to 7 inclusive from any given position

to the next position with reference to the heating jets 23 to 26 inclusive and other fixed parts of the machine.

Reference has been made to the rotatable heads 1 to 7 inclusive. These heads are identical in construction, and hence one only need be described, such as is shown in part section of Fig. 4 of the drawings and corresponding to the rotatable head 5 in Fig. 3. Referring to Fig. 4, the head 5 is shown as including a base 60 having a cylindrical downward extension 61 passing through a base support 62 of the turret 21 and terminating in a tooth gear 63 fixedly secured to the extension 61 by the key 64 and nut 65. The base supports 62 in all the rotatable head units are extended to form depending skirts 66 enclosing the gears 63 except at the side adjacent the rubber-faced wheels 40, 47, 48, 49 and 50, as shown in Fig. 3 of the drawings with reference to the head 3. A suitable roller bearing is interposed between the head base 60 and the base support 62.

The base 60 extends upwardly and terminates in a hollow tube or sleeve 68 having a split side with outstanding lugs 69 through which the adjusting bolt 70 is passed to vary the diameter of the sleeve. The sleeve 68 is adapted to receive the fixture 71 which consists of a short tube having an enlarged head 72, the top of which is flat and provided around its periphery with a plurality of upstanding pins 73 inwardly notched as at 74 to receive the ring 18 which forms the intermediate connection between the stem edge 12 and the envelope 17. This ring, in the form shown in Fig. 5 of the drawings and as illustrated in Fig. 4, consists of a flattened disc-like portion 75 provided with an annular ridge 76 adapted to form the weld area between the ring and shell. The ring is also provided with an inner annular groove 77 which opens downwardly (Fig. 5) and forms the inner periphery of the ring 18. The groove 77 is relatively deep so as to increase the path of heat flow from the welding ridge 76 to the sealing area at the inner edge of the groove and thus preventing softening of the glass seal in the metal welding operation. The outer periphery of the ring carries a flange 130 extending downwardly and from which the base holding tongues 106 are struck in. Within this fixture and the ring and mounted thereon, the stem unit 10 is positioned with the stem flange 12 resting on the inner wall edge 131 of the groove 77 of the ring, as shown in Fig. 4 of the drawings, and with the exhaust tube 16 extending upwardly. Means for holding the stem centrally in position is provided in a pair of clamping jaws 78 having aligned cooperating grooves adapted to seat over the exhaust tube 16 and hold the same in position. These jaws 78 are integral respectively with the arms 79 provided with handles 80' and pivotally mounted at 80 and 81 on the base 60 of the head. The arms 79 move between the guide members 82, and these arms are also held yieldingly in closed position by means of the coil spring 83 fastened at either end to the arms 79.

Means are also provided in the position on the turret of head 5 for compressing the exhaust tube 16 in order to insure a close seal between the metal and glass, if required. This compression means consists, generally, of the lever mechanism 84 and includes the upright rod 85 mounted on the bed of the machine adjacent the turret, as shown in Fig. 3, and terminating at its top 75

- in a U-shaped support 88 pivotally supporting the rod 87. One end of this rod terminates in a horizontal member 88 in which a screw 89 is mounted with its flattened head 90 downwards.
- 5 This head 90 is adapted to contact with the end of the exhaust tube and may be held in any desired position by means of the lock nut 91. The other end of the lever rod 87 is pivotally connected to connecting rod 92, which in turn 10 is pivotally connected to the cam lever 93 in the base of the machine beneath the turret. The cam lever 93 is pivotally supported by the downwardly extending bracket 94 and terminates in a roller 95 which is adapted to engage the cam 15 96 formed on the bottom side of the cam disc 97, which in turn is secured to the shaft 98 of the worm wheel 51.
- In employing the mechanism as above described 20 in the welding together of the glass stem unit to the associated metal ring, the operator, in the position of the turret as shown in Fig. 3, applies in positions 1 and 2 of the rotatable heads the ring 18 and the stem unit 10 to the fixture 71, centrally holding the exhaust tube by means of the jaws 25 78 of the hand clamp. At the position of head 3 the gear 63 of the head comes in contact with the driving chain-driven gear 40 which causes rotation of the head, and at this point also the heat of four gas jets is applied to the rotating 30 head. In the position of head 4 the heat of ten gas jets is applied, and in the position of head 5 the heat of twelve gas jets is played onto the rotating head. Toward the end of the heating period of position 5 the cam 96 causes a lowering 35 of the screw head 90, forcing the exhaust tube 16 downwardly a predetermined distance, thus forcing the mass of glass downwardly. At this point in the movement of the turret the applied heat will have been sufficient to cause a softening 40 of the glass flare edge 12, and the pressure of the cam lever will tend to force the softened glass against the inner side of the wall 131 of groove 77 of the ring 18. At the same time the gravitational effect and the pressure of the gas flame 45 will tend to cause the extreme outer edge of the flange 12 to curl over the groove wall 131 so that on leaving this position 5 the flared edge of the glass stem will have taken the position relative to the wall 131 such as is shown in Fig. 5 of the drawings. A reduced heat of six gas jets is applied 50 to the position of head 6, and in the position of head 7 the weld is permitted to cool and removal may be made of the stem at the position of head 1.
- The stem with the ring attached is now in condition 55 for connection to an electrical unit, for example, and for welding with the enclosing envelope. As applied to radio tubes, the various electrode elements such as the plate 100, grid 101, cathode 102, and heater wires 103 are connected 60 to the lead-in and support wires of the stem, and the electrode unit including the stem is placed in the metal envelope 17 on a welding machine. The open base of the envelope 17 includes an outwardly turned flange 104 which rests on the ring 65 ridge 76, and between this ridge and flange the weld is made, sealing the ring 18 to the envelope 17. The envelope may now be exhausted and the exhaust tube 16 sealed off and the base 105 connected to the ring 18 by means of the inwardly 70 turned edge portion 106 being forced into the depressions on the surface of the insulation base 105. Also, the external terminals 107 are connected to the lead-in wires, as shown in Fig. 5, this completing the manufacture of the tube.
- 75 Modifications of the structure of the ring may be made such as shown in Figs. 6, 7 and 8 of the drawings. In Fig. 6 there is illustrated a modified form in which the ring 110, instead of having a deep inner groove, is provided with a relatively shallow groove 111 adapted to receive the flared 5 edge of the stem 11, practically the entire groove space being filled by the glass. This makes a substantial and effective seal.
- In the modification of Fig. 8 the construction of the ring 112 differs from those of Figs. 5 and 10 6 in that the inner disc grooves are replaced by an inner flange 113, extending toward the base 105. A purpose of the flange is to permit lowering of the stem unit with the attached electrode units, thereby decreasing the overall length of the 15 tube above the upper base line.
- In the modification of Fig. 7 the ring 114 is provided with a simplified annular recess 115, the disc portion being offset to form an inner shoulder on which the flared edge 12 of the stem rests 20 and between which the seal is made between the metal and the glass.
- In constructing these various modifications as well as the preferred form, the exhaust tube and lead-in wires are protected from heat by the 25 shields 141 attached to the arms 79.
- A modified type of fixture as shown in Fig. 2 30 may be utilized in the formation of the weld between the stem and ring of the modification of Fig. 7. Referring to this figure, the fixture 116 is shown with a separable top plate 117 attached to the fixture by the machine screw 118 and provided with a plurality of pins 119 about its periphery, as in Fig. 4. Similarly, each of these pins is cut away to form a ledge 120, opening centrally, on which the ring 121 is adapted to rest. The flared edge 12 of the stem 11 is adapted to rest on the annular inner shoulder of the ring, as shown in Fig. 2, the other mechanism of the device being the same as described in the preferred form of the invention. In the head of Fig. 4, as well as in this modified head of Fig. 2, it is apparent that heat may be applied between the pins as well as above them, thus accomplishing a thorough and rapid heating operation. 45
- In forming the weld between the metal and the glass it is desirable, of course, that the coefficient of expansion from heat be approximately the same in order to avoid fracture from variation in expansion and contraction of the two substances. I have found that copper-clad steel is 50 satisfactory for the metal when used in connection with a soft glass. By copper-clad steel I refer to steel mechanically coated with a thin layer of brass and an outer coating of copper. This 55 unit is heat treated and cold drawn to produce the copper-coated steel. Other methods of obtaining a copper coat, such as electrolytic methods, may of course be employed, provided the coefficient of expansion of the resultant structure is similar to that of glass. Also, other substances such as molybdenum or special alloys may be used. While soft glass is used in the stem structure, other glass-like or vitreous substances may also be 60 employed, provided the coefficient of expansion of the metal and insulator are substantially the same. 65
- It is pointed out that in the completed construction of the enclosure including the metal envelope, the ring and stem, that the entire internal electrical units are supported on a homogeneous insulation unit of glass, as distinguished from supporting each conductor or metal support upon separate and spaced insulation elements. By this construction, as is clearly 70 75

brought out in Fig. 5, the danger of short circuiting between the lead-in wires and supports is practically eliminated and detrimental capacity and inductive effects reduced. It is pointed out, further, that the non-planar, as distinguished from the plane, alignment of the lead-in wires and supports permits, for the same number of conductors, increased separation, thereby reducing undesirable inter-capacity and inductive effects between these conductors. The circular wire arrangement is preferable, although any other configuration of the wires, such as triangular or square, might be used.

Attention is directed also to the utility of the combination of a crown-shaped stem, ring and metal envelope, in that the axially extending space of the envelope occupied by the stem support is practically negligible. This permits a minimum length of over-all tube construction.

20 The embodiments shown and described pertain to radio tubes, but application of the invention may obviously be made to any electrical apparatus requiring a gas sealed metal container. Also, these embodiments may be modified and 25 therefore I do not wish to be limited thereto except as required by the appended claims.

What I desire to claim is:

1. A tube construction comprising a tubular metal envelope closed at one end and provided 30 with an inwardly projecting flange at the other end, a dish-shaped glass stem projecting into said envelope and hermetically sealed at its outer circumference to said flange, and a plurality of conductors sealed to and extending through said stem.

2. A tube construction comprising a tubular metal envelope closed at one end and provided with an inwardly projecting flange at the other end, a dish-shaped glass stem projecting into 40 said envelope and hermetically sealed at its outer circumference to said flange, and a plurality of conductors sealed to and extending through said stem, said conductors being arranged in approximately circular formation whereby maximum 45 displacement between them is secured, the thickness of the base of the stem being variable.

3. A tube construction comprising a tubular metal envelope closed at one end and provided with an inwardly projecting flange at the other 50 end, a dish-shaped glass stem projecting into said envelope and hermetically sealed at its outer circumference to said flange, and a plurality of conductors sealed to and extending through said stem, said glass and envelope flange having substantially the same coefficient of expansion for 55 heat and said flange lying in a plane approximately perpendicular to the envelope axis.

4. An electric tube construction comprising a tubular metal envelope having a closed end, an 60 inwardly and transversely projecting metal flange welded to the open end of said envelope, said flange defining an opening in the envelope, a glass wall forming a closure for said opening, a plurality of metal conductors passing through 65 said wall, said wall having an increased thickness adjacent each of said conductors.

5. An electric tube construction comprising a tubular metal envelope having a closed end, an inwardly projecting metal flange welded to the 70 open end of said envelope, said flange defining an opening in the envelope, a glass wall forming a closure for said opening, a plurality of circularly arranged metal conductors passing through said wall, said wall having an increased thickness adjacent each of said conductors, and means in-

cluding a glass tube centrally positioned in said wall for facilitating removal of gases from said envelope, the metal of the flange and the glass of the wall having substantially the same coefficient of expansion for changes of temperature, 5 and said central tube and conductors being separated by a grooved area.

6. A tube construction comprising a tubular metal envelope closed at one end and an outwardly extending flange at the other end, a flattened ring having an annular ridge welded to said outwardly extending envelope flange, said ring having an inner axially extending flange forming a central opening to said envelope, a glass wall forming a closure of said opening, the edges of 15 the wall being sealed to the flange of the ring, said wall being provided with means for facilitating the removal of gases from said envelope, a plurality of conductors sealed to and extending through said wall, no three of said conductors being positioned in a common plane, an electrode assembly mounted within the envelope and connected to said lead-in wires, an insulation base enclosing the glass wall of the envelope, said ring having inwardly extending fingers entering recesses on the periphery of said insulation base to retain the same in position, and a plurality of terminals in the insulation base connected to said lead-in wires.

7. An electric tube construction comprising a 30 tubular metal envelope having one end closed, an inwardly projecting and flattened ring welded to the other end of said envelope, said ring being provided with an axially extending and outwardly opening groove on the inner periphery of 35 the ring, a glass support forming a closure for the opening bounded by the inner wall of said ring groove, a portion of the glass of the wall being molded over and sealed to the inner edge of the groove to form a gas seal, a plurality of conductors passing through and sealed in said glass wall, electrode elements mounted within the envelope on said glass wall and connected to said conductors, means in said glass wall for facilitating removal of gases within the envelope, and an insulation base mounted adjacent the glass wall and enclosing the same, said base being supported by holding members attached to the outer edge of said ring, and a plurality of terminals secured to said base and to said conductors. 50

8. A tube construction comprising a tubular metal member closed at one end, a flattened ring secured to the other end of said envelope, said ring having an inwardly projecting shoulder forming the boundary thereof, a glass stem having a flared edge sealed to said shoulder, said wall having means for permitting the removal of gases within the envelope, a plurality of conductors sealed to and passing through said stem, electrode elements mounted within the envelope and attached to said conductors, an insulation base enclosing the stem and attached to said ring, and a plurality of terminals positioned in the base and connecting to the conductors. 55

9. The process of making gas sealed metal tubes which consists in forming a shallow dish-shaped stem including a flattened central portion and a flared edge and a tubular exhaust stem opening therethrough, applying the edge of a metal ring to the flared edge of the stem while 70 simultaneously subjecting the contiguous contacting areas of glass and ring to heat and pressure, and welding a metal envelope to the outer edges of said ring.

10. The process of making electric tubes which 75

comprises forming a shallow dish-shaped stem of glass with a plurality of conductors sealed therein, applying to the edge of said stem a ring of metal while simultaneously subjecting the contacting areas of metal and glass to the combined action of heat and pressure, mounting on the stem and connecting to said conductors a plurality of electrode elements forming an electrode assembly, enclosing said electrode assembly by a metal tube closed at one end and welded to the metal ring at the other, removing the gases from the interior of the envelope, and applying an insulation base to the envelope containing terminals connected to said conductors.

15 11. In a metal radio tube construction, a base-end closure therefor comprising a flattened and centrally apertured metal ring, an annular groove bounding the edge of the aperture said groove opening outwardly, a mass of vitreous material forming a closure for the aperture, and a plurality of conductors passing through and sealed in said vitreous material.

20 12. In a metal radio tube construction a base-

end closure therefor comprising a flattened and centrally apertured metal ring, an annular groove bounding the edge of the aperture, said groove opening outwardly, a mass of vitreous material forming a closure for the aperture, a plurality of conductors passing through and sealed in said vitreous material, and an exhaust tube sealed in said material. 5

13. The process of making a base assembly for a metal tube which comprises positioning a glass mass in the aperture of a base ring, applying heat to the glass to make the edge thereof plastic, and applying pressure to the glass to force the material closely against the aperture edge.

14. The process of making a base assembly for a metal tube which comprises positioning a glass mass in the aperture of a base ring, applying heat to the glass to make the edge thereof plastic, applying pressure to the glass to force the material closely against the aperture edge, and 20 blowing an exhaust opening through said wall.

CLARENCE A. HORN.
